(57) **CLAIM**

I claim the ornamental design for an assembly of bobbin
holders and a stand, as shown and described.

DESCRIPTION

FIG. 1 is a perspective view of an assembly of bobbin holders
and a stand according to my new design;

FIG. 2 is a front view of the same assembly;

FIG. 3 is a rear view of the same assembly;

FIG. 4 is a top plan view of the same assembly;

FIG. 5 is a bottom view of the same assembly;

FIG. 6 is a right side view of the same assembly;

FIG. 7 is a left side view of the same assembly;

FIG. 8 is a perspective view of a bobbin holder to be incor-
porated in the assembly shown separately for the comple-
teness of the illustration;

FIG. 9 is a front view of the bobbin holder;

FIG. 10 is a rear view of the bobbin holder;

FIG. 11 is a top plan view of the bobbin holder;

FIG. 12 is a bottom view of the bobbin holder;

FIG. 13 is a right side view of the bobbin holder;

FIG. 14 is a left side view of the bobbin holder;

FIG. 15 is a perspective view of a stand to be incorporated in
the assembly shown separately for the completeness of the
illustration;

FIG. 16 is a front view of the stand;

FIG. 17 is a rear view of the stand;

FIG. 18 is a top plan view of the stand;

FIG. 19 is a bottom view of the stand;

FIG. 20 is a right side view of the stand; and,

FIG. 21 is a left side view of the stand.

The broken lines in FIGS. 5, 12, and 19 are included for the
purpose of illustrating portions of the assembly of bobbin
holders and a stand that form no part of the claimed design.
